UNITED STATES PATENT OFFICE.

CARL H. BISSELL, OF SYRACUSE, NEW YORK, ASSIGNOR TO CROUSE-HINDS COMPANY,
OF SYRACUSE, NEW YORK, A CORPORATION OF NEW YORK.

PORCH-LIGHT.

1,382,267.

Specification of Letters Patent. Patented June 21, 1921.

Application filed June 21, 1918. Serial No. 241,220.

To all whom it may concern:

Be it known that I, CARL H. BISSELL, a citizen of the United States, and a resident of Syracuse, in the county of Onondaga and 5 State of New York, have invented a certain new and useful Porch-Light, of which the following is a specification.

This invention relates to electric conduit outlet boxes and has for its object what for 10 convenience is called a porch light which is particularly simple in construction and highly efficient and durable in use, and in which the numbers or other sign are readily accessible, and adjustable to face in the 15 desired direction; and the invention consists in the novel features and in the combinations and constructions hereinafter set forth and claimed.

In describing this invention, reference is 20 had to the accompanying drawings in which like characters designate corresponding parts in all the views.

Figure 1 is a vertical sectional view, partly in elevation of this porch box.

25 Fig. 2 is a sectional view on line 2—2, Fig. 1.

Fig. 3 is a sectional view on line 2—2, Fig. 1, the lower section being shown in elevation and being partly displaced out of its 30 normal position.

Fig. 4 is a fragmentary detail view illustrating the means for holding the glass panels in position and for detachably locking the lower section to the upper.

35 This porch box comprises, generally, upper and lower sections, the lower section being detachably and reversibly mounted on the upper section and having front and rear transparent faces arranged at an angle to 40 each other.

The upper section 1 is in the form of an 45 elongated rectangular box having flanges 3 at its ends for securement to a suitable support and also having means for connection to an electric conduit as a nipple 4, here shown as adjustably mounted in an upwardly extending neck or nipple 5 on top of the section 1, the nipple 4 being adjustable to different angles in order to make connection 50 with the electric conduit inclosing the service wires. In different installations, the conduits are located differently relatively to the box and hence the nipple 5 being adjustable is adaptable to the different positions 55 of the conduits. The box is also provided

with means as a bracket 6 for supporting an electric lamp socket 7 in horizontal position in the section 1 and is open at its lower side.

The section 2 is shown as having a vertical front side wall 8 and an inclined rear wall 9 converging downwardly to the lower edge of the front wall 8, the walls 8, 9 being provided respectively with openings or windows 10, 11 extending throughout the greater portions of said walls 8 and 9. 60

These openings are closed by transparent or translucent glass panels 12 and 13 arranged on the inner side of the section 2 and held in position by spring pressed means.

The panel 12 on the vertical side of the 70 section 1 is preferably shown as formed of two layers of glass, the rear layer of which is translucent, and the street numbers or other information are inserted between the 75 layers of glass. In the day time these numbers show up plainly against the translucent layer, and at night they show up equally plainly when the lamp is illuminated as the light passes through the translucent layer.

The panel 12 has its lower margin inserted 80 between the lower margin 14 of the opening 10 and shoulders 15 located in the rear of and spaced apart from the margin 14 and the upper edge of the panel 12 is located below a rib 16.

The panel is held in position by spring 85 clips 17 at the opposite end margins of the vertical wall and overlying the end margins of the glass panel 12. To remove the glass panel for the purpose of inserting the numbers or for any other purpose, the upper edge of the panel 12 is pressed inwardly 90 against the action of the spring clips 17 until the upper edge of said glass panel clears the rib 16 when the panel is pushed upwardly and removed and the numbers are inserted between the layers thereof. It is replaced by the reverse of this operation.

The panel 13 on the inclined side of the 100 box is of corrugated or prismatic glass and is held in position by spring tongues 18 pressing on the opposite end margins thereof of which are located in the rear of the end margins of the wall formed with the opening 11.

The lower section 2 is detachably and 110 reversibly mounted on the lower side of the upper section, and as here shown, the upper section is formed with internal lugs or shoulders 19 at its lower corners at opposite

sides of the lower open side of the section, and the lower section is provided with hook-shaped lugs or shoulders 19^a coacting with the shoulders 19 on one side of the open side 5 of the section 1, and with spring pressed tongues 20 having hook shaped ends 21, coacting with the set of lugs or shoulders 19 on the opposite side of the section 1, the tongues 20 being depressible to disengage 10 them from the contiguous shoulders 19, by buttons 22 extending through the wall 10.

The reversible feature of the lower section 2 is particularly advantageous in that in installing the upper section on porches, 15 etc., the pipe or electric conduit containing the service wires is attached to the nipple 4 from any direction that happens to be convenient without regard to the position to be occupied by the section 2, or in other words, 20 the section 1 is mounted in any position it happens to come or which suits the workman, and therefore in order to meet this condition the lower section is made reversible so that its vertical side will face the 25 street, and its inclined side will come parallel to the incline of the steps.

The spring pressed tongues 20 and 18 are here shown as bent from a single piece of metal and the spring clips 17 and the tongues 30 20 and 18 are held in position by fastening screws 24 common to all of said parts.

In operation, the section 1 is placed on a suitable support as an overhead beam on the porch and connection made with an electric 35 conduit, the nipple 4 being adjustable in order to facilitate the adjustment of said nipple to the position of the conduit, and as the vertical side through which the numbers are exposed faces forwardly and the inclined side rearwardly toward the steps of the porch, in order that such positioning of the section 2 may be brought about in different installations, the section 2 can be readily detached and reversed to bring about the 45 proper facing of its walls 10 and 11.

What I claim is:

1. A porch light of the class described comprising a box including upper and lower sections, the upper section being provided 50 with means for connection to an electric conduit and with means for supporting an electric lamp socket, and the lower section being provided with transparent faces on opposite sides thereof, one face being vertical and the other being inclined and converging toward the lower edge of the vertical face and adapted to throw light downwardly and the lower section being reversibly and detachably mounted on the upper 55 section and being reversible to position the inclined face whereby it is adapted to project light on the steps of a porch, substantially as and for the purpose described.

2. A porch light comprising a box includ-

ing upper and lower sections, the upper section having means for connection with an electric conduit, and means for supporting an electric lamp socket, the upper section being open at its lower side and provided with shoulders at opposite ends of the open 70 side, the lower section being open at its upper side and detachably mounted on the lower side of the upper section and having fixed shoulders for interlocking with the shoulders on either side of the upper section, 75 and latches coacting with the shoulders on the opposite side of the upper section, substantially as and for the purpose described.

3. A porch light comprising a box including upper and lower sections, the upper 80 section having means for connection with an electric conduit, and means for supporting an electric lamp socket, the upper section being open at its lower side and provided with shoulders at opposite sides of the open 85 side, the lower section being open at its upper side and detachably mounted on the lower side of the bottom section and having fixed shoulders for interlocking with the shoulders on either side of the upper section, 90 and latches coacting with the shoulders on the other side of the upper section, and operating means for the latches extending through the contiguous side of the lower section, substantially as and for the purpose 95 specified.

4. A porch light comprising a box including upper and lower sections, the upper section having means for connection with a conduit, and means for supporting 100 an electric lamp socket, the upper section being open at its lower side and the lower section being open at its upper side and including front and rear walls arranged at an inclined angle to each other, the rear wall 105 converging downwardly toward the front wall, the front and rear walls being formed with openings and with glass panels covering the openings, spring means arranged on the inside of the box and behind the margins of the walls at the ends of the openings, for holding the panels in position, the lower section being detachably and reversibly mounted on the open side of the upper section, and means for detachably holding 110 the lower to the upper section in either of its positions including spring catches arranged inside of the lower section and operable from the outside thereof and being located in the rear of the margins of one of 115 the walls at the ends of the opening therein, substantially as and for the purpose specified.

In testimony whereof, I have hereunto signed my name, at Syracuse, in the county 125 of Onondaga, and State of New York, this 7th day of June, 1918.

CARL H. BISSELL.
